UNITED STATES PATENT OFFICE

2,620,906

ATTACHING CLIP FOR WALL SURFACING

Morris Ketchum, Jr., New York, N. Y., assignor
to The Kawneer Company, Niles, Mich., a cor-
poration of Michigan

Application January 30, 1947, Serial No. 725,404

4 Claims. (Cl. 189—88)

1

The present invention relates to construction materials and more specifically to the combination of a facing material as disclosed in Miller Patent No. 2,511,074 and in Knott Patent No. 2,591,361, with improved mounting devices whereby it may be mounted on a supporting wall to form an ornamental exterior surface for the wall. The invention is of equal utility for interior walls.

Materials of this general type are used for many and varied purposes but they are particularly well suited to the construction of store fronts, etc., or any similar installation where a pleasingly patterned surface of attractive and modern appearance is essential. In view of the wide variety of materials that have been utilized for this purpose, it is believed necessary to briefly review the problems incident to such installations, so that difficulties apt to be encountered may be kept in mind and the advantages obtained by the use of a facing material and mounting means such as here disclosed can be fully appreciated.

It will be remembered that materials of this type are not only adapted for application to new buildings, but are also often used to modernize existing structures, in which case they are applied over the present wall surfaces to conceal unsightly walls and to enhance the appearance of the building. It follows that they are often applied to irregular or oddly shaped areas; and it is therefore essential that the material be capable of easy installation and easily cut to fit the areas to be covered. Moreover, it should be remembered that since the materials are often applied to existing structures having existing ledges, windows, or other peculiarities of construction, it is not always practicable to mount the furring strips on which the facing is carried in an exactly uniform pattern, or with exactly accurate spacing between various strips.

Possibly even more important is the fact that facing materials may be used on buildings in which the supporting wall is not entirely stable and that in some instances a certain amount of settling or shifting of the supporting walls is to be expected. Obviously, to cope with such a condition, it is essential to provide a facing material with mounting devices which are not only easy to install, but are so constructed that the surface of the facing material is not distorted by reasonable shifting of the supporting wall, so that the attractiveness of its appearance will not be diminished.

The general aim of the present invention is to provide an improved facing material assembly that is more acceptable than those previously

2

known in that it is more easily installed and is also more satisfactory in use since it presents a more pleasing appearance and is less subject to accidental damage. More specifically, it is one of the objects of the invention to provide a sectional facing surface wherein the surface is applied in small sections joined to each other by joints that are inconspicuous, yet with mounting means sufficiently yieldable so that the assembly may not only compensate for expected thermal expansion, but may also permit its individual parts to shift sufficiently to avoid damage due to any reasonable sagging or shifting of the supporting wall.

A further object of the invention resides in the provision of a sectional facing assembly as indicated, with improved mounting devices so that the sections of the facing material may be supported entirely on a number of furring strips secured to the supporting surface, in order that the devices by which the panels are secured are entirely enclosed, so that they will be invisible from the exterior surface of the wall and protected against physical damage and against exposure to the elements.

A still further object of the invention resides in the provision of a mounting clip consisting of a single sheet metal stamping so formed as to include frictional surfaces to engage a furring strip shiftably but with sufficient friction to secure the clip and facing panel in place, together with a bracket arranged to slidably engage the edges of the individual panels of the facing material, but exert a sufficient frictional grip to anchor the panels in position with respect to the furring strips.

A further object of the invention resides in the provision of a facing material including furring strips adapted to be secured to a supporting wall, exterior facing panels, and mounting means for securing the facing panels to the furring strips, wherein all of the parts of the assembly are formed of relatively thin sheet material, and wherein the individual parts comprise a multiplicity of identical pieces, so that the material is readily adaptable to economical mass production methods of manufacture and is equally well adaptable to installation on large or small areas and to regular or irregular surfaces.

The foregoing objects are accomplished in the teachings of this invention by the provision of facing panels consisting of generally flat sheets of thin material having a number of longitudinal channels formed therein to give the material additional rigidity and provide a surface pattern

for the panels, together with furring strips adapted to be secured to any supporting surface and mounting clips arranged to be set in the furring strips and to support the individual panels of the facing. It is contemplated that the material may be mounted in either vertical or horizontal position and that the channels formed in the material may run either vertically or horizontally, but in any event the panels will be positioned at approximately right angles to the strips, so that a number of mounting clips may be positioned along the edges of each individual panel to anchor the panel to every furring strip over which it extends.

A preferred commercial embodiment of the invention is illustrated in the drawings attached to and forming a part of this specification, in which:

Figure 1 is a perspective view of a section of facing material as contemplated by this disclosure, illustrating the method of mounting the material on a supporting surface and the means by which adjoining panels of the material are coupled to each other.

Figure 2 is a perspective view of one of the mounting clips by which the panels are secured to the furring strips.

Figure 3 is a sectional view through the facing material, the view being taken substantially on the center line of one of the furring strips.

Figure 4 is a detail sectional view of a supporting filler, the view being taken substantially on the plane of the line 4—4 in Figure 3.

Figure 5 is a detail sectional view through a joint between the sides of adjoining panels, showing a mounting clip in position. The view is taken substantially on the plane of the line 5—5 of Figure 3.

Figure 6 is an end elevational view of one of the types of panels contemplated by this invention, together with a coupling sleeve fitted in position against the inner panel surfaces.

Figure 7 is an end elevational view of a modified form of facing panel.

Figure 8 is an end elevational view of another modified form of panel.

Figure 9 is a front elevational view of one of the furring strips, showing the manner in which the mounting clips are secured.

Figure 10 is a detail sectional view of a mounting clip and furring strip, taken substantially on the plane of the line 10—10 of Figure 9.

Figure 11 is a detail sectional view taken substantially on the plane of the line 11—11 of Figure 9, and

Figure 12 is a detail sectional view of a corner fitting.

In installing the material disclosed in this application, it is contemplated that the individual panels will be mounted on and secured to some supporting wall, here represented by the surface 10. A plurality of furring strips 11 are mounted on the wall in any convenient manner, as by the screws 12 in the screw holes 13 at spaced intervals along the back portion 14 of the strips, each of which consists of a relatively wide shallow channel having side flanges 15 and a pair of lips 16 extending inwardly from each of the side flanges. The furring strips 11 are adapted to receive a number of mounting clips 20 each consisting of a stamping punched out of a single piece of sheet metal and formed to include a mounting portion adapted to be received in the furring strip and frictionally secured, together with a bracket portion extending outwardly from the furring strip and having means to engage

the edges of the individual panels of facing material to anchor the panels to the strips.

The mounting clip includes an arched center portion 21 which bridges the center of the back wall of the furring strip to clear the heads of the supporting screws and terminates in a pair of outwardly curving folds 22 which form convex contact surfaces on the lower side of the clip, to bear against the back surface 14 of the furring strips 11. The arch 21 is raised to approximately the full height of the furring strip, however, so that the clips can be inserted in the channel and slid along the strips to any desired point, and will clear the heads of any of the supporting screws 12. The clips 20 also include a pair of spring wings

23 extending outwardly and upwardly from the folds 22 and curved in cross section in two planes, so that the upper surfaces of the wings comprise convex frictional surfaces adapted to fit under and bear against the lower surface of the lips 16. The convex contact surfaces of the clip exert a high degree of friction, but have no tendency to bind or lock the clips against movement. Thus the clips inserted in the furring strips can be moved along the channel by force, but secure themselves in position by friction sufficient to provide an adequate mounting for the individual sections of the facing material. To this end each of the clips includes a bracket portion 24 ex-

30 tends outwardly from the center arch 21 and terminating in a pair of anchor tabs 25 spaced apart from each other and adapted to lie over and engage the edge flange of one of the panels. The anchor tabs are each provided with upturned ends to contact the inner surface of the furring panels and hold the tabs down, and with latch hooks 26 struck downwardly from the tabs to prevent displacement of the panel with respect to the clip. These anchor tabs also prevent rotation of the clip with respect to the panels and furring strips. The bracket 24 of the clip also

35 includes a spring tab 27 extending outwardly between the tabs 25 to act as a pressure pad adapted to bear upwardly against the inner side of the tongue of the panel to aid in effecting a tightly sealed joint between the individual panels.

The clips 20 are of a length considerably greater than their width; that is, the distance between the outer edges of the wings 23 is somewhat greater than the length of the arch 21, so that the clip may be inserted into the furring strip by dropping it in position with the arch 21 perpendicular to the length of the furring strip and then rotating the clip 90 degrees through the position shown at the left of Figure 9 to the final position illustrated at the right of Figure 9. The outer surfaces of the wings 23 are curved as indicated at 28 so that the clip may be rotated without wedging against the flange 15 of the furring strip. It may also be noted that the bracket portion 24 extending upwardly from the clip includes a pair of clearance notches 29 on its opposite sides to define a relatively narrow neck portion in the plane of the lips 16, so that as the clip is rotated into position and passes through the position indicated at the left of Figure 9 the inwardly extending lip 16 on the flange 15 of the furring strip will not strike the bracket, but will enter the notch 29 so that the bracket will be free of interference with the lips 16 as the clip is inserted.

The individual sections of the facing material each consist of a generally flat panel having a number of regularly spaced flat bottom channels 75 extending longitudinally of the panel to define

a number of relatively long and narrow outer face surfaces 31, spaced apart by lower face surfaces 32 at the bottom of each of the channels. The channel walls 33 are preferably at an obtuse angle with respect to the surfaces 31 and 32, and one edge of the panel terminates in a wall 34 similarly inclined and joining the outer face surface 31 with a flat tongue 35 terminating in an inwardly extending perpendicular flange 36. The flat tongue 35 is preferably of greater width than the lower face surfaces 32 of the channels to provide a marginal sealing surface 37 adapted to be received in a groove or coupling socket of an adjoining panel.

The coupling socket 40 on the opposite edge of 15 the panel includes an inwardly inclined surface 38 forming a reverse bend to provide an inner sealing surface 39 in the same plane as the lower face surfaces 32 and the sealing surface 37, but oppositely disposed. The socket includes a second reverse bend 41 connecting the portion 39 with a flat portion 42 comprising a mounting surface and terminating in a short perpendicular flange 43. The flange 43 is located beyond the edge of the reverse bend 38 and extends upwardly to a point just short of the plane of the inner sealing surface 39 so that when a pair of identical panels are joined, the sealing surface 37 of the tongue 35 on one panel will bear against the inside sealing surface 39 of the coupling socket. (Figure 3.)

The tongue 35 of one panel will be received in the coupling socket 40 of the adjoining panel with the sealing surface 37 bearing directly against the inner sealing surface 39 of the socket. The flange 43 will be engaged under the pair of anchor tabs 25 to force the mounting surface 42 against the lips 16 of the furring strip. The latch hooks 26 will prevent the flange from being disengaged from the tabs, yet will permit longitudinal shifting of the panel in response to a force great enough to overcome the friction between the parts.

The center tab or spring pressure pad 27 will engage the rear surface of the tongue 35 and urge 45 it outwardly to force the sealing surface 37 into firm engagement with the inner sealing surface 39 so as to effect a tight, weatherproof joint. In this connection it will be noted that the flange 36 at the end of the tongue will tend to maintain the tongue straight and true and thus assist in establishing an adequate seal between the sections and that the flange 43 of the coupling socket is positioned beyond the reverse bend 38. This aids in positioning the clips on the flange 55 and facilitates in the insertion of the tongue of one panel in the socket of the next adjoining panel as the material is installed.

The individual sections of the material may be formed in any convenient width and length, and with or without the longitudinal channels. The form illustrated in Figure 6 includes three channels, while the form illustrated in Figure 7 includes identical parts designated by the same reference numerals, but with only a single channel. Various other modifications may be desirable to facilitate installation of this type of surface on irregular areas and it is contemplated that double edged panels, such as the panel illustrated in Figure 8, which has coupling sockets 40 on each edge, may be provided, and that necessary types of termination fittings or angle brackets, such as the typical corner bracket shown in Figure 12 may be desirable. Here an angle strip 44 has a short flange 45 at each edge, so that it 75

forms two tongues to fit into the coupling sockets 40 of panels at a right angle to each other.

Means may also be provided to give internal support to the individual panels between their opposite edges. For this purpose a filler block 46 is provided. As shown, this comprises a short inverted channel having a flat top adapted to lie against the inner surface of one of the surface channels of the panel, and carried on a pair of flanges 47, each of which is pierced at 48 to provide latching means adapted to snap under the lips 16 of the furring strips to hold the block in place.

The joints between the adjoining ends of contiguous panels are held in perfectly fitted relationship, so that the joint line is inconspicuous and practically invisible. This is best done by means of coupling sleeves formed to exactly fit the inner surface of the panels and fitted between adjoining panels at the joints. In Figure 1 a coupling sleeve 51 formed to fit a panel of three channel width is shown fitted into the panel 52 and extending upwardly from the end of the panel so that the lower end of a similar panel to be mounted above the panel 52 will be held in exact registry with the lower panel. Similarly, a joint between a pair of single channel sections is illustrated at the lower corner of Figure 1, where the upper panel 53 and lower panel 54 are coupled by a sleeve 55 designed to fit the inner surfaces of the individual panel sections. The configuration of a coupling sleeve designed for and adapted to be used with a three-channel section is illustrated in Figure 6 where it will be seen that the front surface of the coupler or sleeve 51 conforms exactly to the inner surface of the individual panel.

From the foregoing it will be apparent that the teachings of this disclosure provide a facing material having important practical advantages in that it is inexpensive to manufacture and relatively easy to install, yet provides a neat and highly attractive surface wherein the joints between the individual panels are adequately sealed yet are completely inconspicuous and practically invisible, so that the area covered with the material gives the appearance of being a single uninterrupted surface. Moreover, the material includes anchoring devices that may shift their position in response to extreme forces and yet be undamaged and continue to perform this function, so that the material is capable of compensating for thermal expansion of the materials and also for any reasonable shifting or flexing of the supporting surfaces which might buckle or crack other types of surfacing. It thereby provides an ideal surfacing material that may be depended upon to maintain an attractive and proper appearance irrespective of ordinary hazards.

The teachings of this invention also provide a simple convenient and efficient means for mounting individual facing panels on a supporting surface, so that it is only necessary to secure the furring strips to the surface and snap the individual panels in position by the spring clips here disclosed. It is unnecessary to have exact alignment of the furring strips with each other or to have the individual furring strips spaced apart at exact distances or even with regular intervals, since the clips will anchor the panels to the furring strips at any point of intersection. This is important in applying facing material to existing structures since it is not always practicable to provide exactly aligned furring strips,

nor is it always feasible to position the strips at an exact distance from each other or at perfectly regular intervals.

In conclusion, it is submitted that the present disclosure provides a facing material that is at once well adapted to economical manufacture and adapted for quick and easy installation on any type of supporting wall, characterized by a neat, modern and attractive appearance, capable of resisting damage due to instability of the supporting walls and thus likely to maintain an attractive appearance permanently, and, in short, ideally suited to its intended purpose.

The construction of the clips possesses many outstanding advantages due to the fact that the center arch 21, wings 23, bracket 24, pad 27, and tabs 26 are all integral, and formed from one unitary piece of resilient sheet material. The clip construction is therefore unusually strong, but resilient in all of its parts, so that the panels are yieldably but firmly held secured in position with respect to the furring strips. Additionally, the clips are snapped onto edge flanges of the panels and yieldably but firmly hold the panels in place, with the joints between the panels elastically yet securely sealed.

The exact form of the invention illustrated in the drawings and described in this specification is the present commercial embodiment of these teachings and is believed to be well illustrative of the inventive thought involved. It is recognized, however, that certain variations of mechanical design are feasible without sacrifice of all of the advantages inherent in this disclosure and it is accordingly pointed out that the scope of the invention extends to any modification or variation coming within the terms of the appended claims.

Having thus described the invention, what I claim as new and desire to protect by United States Letters Patent is:

1. As an article of manufacture, a fastening clip comprising a sheet metal plate having an arched center section terminating in outwardly curved folds, said folds including convex frictional lower contact surfaces adapted to bear on the bottom of a channel shaped furring strip; a pair of spring retaining wings extending upwardly and outwardly from the curved contact surfaces on each side of the channel portion to engage lips on the side flanges of the furring strip, said wings being curved in cross section to provide convex upper frictional contact surfaces thereon, the length of the arched center section of the clip being substantially less than the span between the outer edges of the wings and the outer edges of the wings being curved so that the clip may be freely inserted between the lips of a furring strip and rotated to lock the wings under the lips; together with a bracket formed integrally with the arched portion and wings and extending outwardly from the strip: the bracket having a wide end remote from the arched portion with a spring pressure pad and a pair of anchor tabs at the outer end, and having notches on each side to define a narrow neck between the arched portion of the clip and the outer end of the bracket.

2. As an article of manufacture, a fastening clip comprising a sheet metal plate having an arched center section terminating in outwardly curved folds, said folds including convex frictional lower contact surfaces adapted to bear on

the bottom of a channel shaped furring strip; a pair of spring retaining wings extending upwardly and outwardly from the curved contact surfaces on each side of the channel portion to engage lips on the side flanges of the furring strip, said wings being curved in cross section to provide convex upper frictional contact surfaces thereon, the length of the arched center section of the clip being substantially less than the span between the outer edges of the wings and the outer edges of the wings being curved so that the clip may be freely inserted between the lips of a furring strip and rotated to lock the wings under the lips; together with means secured to one end of the arched center portion to engage the edge of a facing panel and secure the panel to the furring strip.

3. The combination, with a furring strip having a flat back wall, a pair of perpendicular flanges along the opposite sides of the back wall, and inwardly extending lips at the upper edge of said flanges to form a rectangular channel, of a fastening clip having an arched center section bridging and substantially spaced away from the center of the back wall of the channel to clear mounting screws therein; a smoothly rounded convex contact surface at each side of the arched section bearing against the back wall of the strip; a pair of spring retaining wings extending upwardly and outwardly from the rounded contact surfaces on each side of the arched section, with a smoothly rounded convex contact surface on the end of each wing bearing against the inner surface of one of the inwardly extending lips of the furring strip flanges to hold the clip in place with firm frictional engagement, yet permit it to be forced longitudinally of the channel without binding against the channel walls or supporting screws.

4. As an article of manufacture, a fastening clip comprising a sheet metal plate having an arched center section adapted to clear fastening means in the center of a channel shaped furring strip, said arched center section terminating in outwardly extending portions which form a pair of frictional lower contact surfaces adapted to bear on the bottom of said furring strip at two places spaced apart from each other, a pair of wings extending outwardly from said contact surfaces to engage inner lips on the side flanges of the furring strip, and a bracket extending outwardly and upwardly from a free edge of said center section of the clip and being provided with panel attaching means.
